UNITED STATES PATENT OFFICE.

KARL E. PEILER, OF HARTFORD, CONNECTICUT, ASSIGNOR TO HARTFORD-FAIRMONT COMPANY, OF CANAJOHARIE, NEW YORK, A CORPORATION OF NEW YORK.

PADDLE OR PLUNGER FOR MOLTEN GLASS.

1,328,799.

Specification of Letters Patent. Patented Jan. 20, 1920.

Application filed March 27, 1917. Serial No. 157,634.

To all whom it may concern:

Be it known that I, KARL E. PEILER, a citizen of the United States, residing at Hartford, in the county of Hartford and State of Connecticut, have invented new and useful Improvements in Paddles or Plungers for Molten Glass, of which the following is a specification.

This invention relates to the construction 10 of a stirrer or paddle or plunger for working in molten glass. It is herein shown and described as designed for use in a machine for feeding or gathering charges of molten glass of uniform size suitable for subsequent 15 pressing, blowing or otherwise shaping to commercial form. Such paddles or plungers are required to operate in or to dip into molten glass, and consequently they are subjected, particularly the head ends, to very 20 high heat.

The object of this invention is to construct a paddle or plunger for a machine of this character in such manner that it is inexpensive to make and durable in use, in that 25 it will not readily bend or break or burn out, or become otherwise impaired as a result of the action of the high heat to which it is subjected when operating in or dipped into the molten glass.

This object is attained by a construction 30 in which an operating head of heat resisting refractory material, such as pot clay, adapted for working in molten glass, is cased in a metallic reinforcement which may 35 serve also as a support by means of which the operating head is attached to a holder or carrier of the machine or apparatus by which the head is operated, and this metallic reinforcement, or carrier, is provided with 40 passages through which air or other cooling medium may be circulated. Being thus kept below the temperature at which it would bend easily, the metal forms a supporting and reinforcing backbone for its surrounding shell 1 of refractory material, which 45 being usually of weak and brittle character, would otherwise break too easily when moved through the hot viscous glass. On the other hand, the refractory material 50 shields the metallic support from direct contact with the intensely hot glass, so that the parts mutually protect each other.

Figure 1 of the accompanying drawings shows a side elevation of a paddle which 55 embodies the invention, with a portion of

the head broken away to show the means for securing the head to the support. Fig. 2 is a plan view in cross-section, taken at the line 2—2 on Fig. 1, illustrating the manner of centralizing the pipe provided for 60 introducing cooling air into the support. Fig. 3 shows a transverse section on the plane indicated by the line 3—3 on Fig. 1. Fig. 4 shows a transverse section across part of the head on the plane indicated by the 65 line 4—4 on Fig. 1. Fig. 5 shows a transverse section across the head on the plane indicated by the line 5—5 on Fig. 1.

The paddle illustrated in the drawings is only one of many forms in which this invention may be applied. Through the head 70 1 and its hub 2 is a central longitudinal core, the lower part 3 of which is larger in diameter than the upper part 4 so as to provide a shoulder 5. The lower part of the 75 core in the head is preferably flattened on one side, as at 6, or otherwise made irregular in shape, to prevent the refractory parts from turning on the metallic support, and in this core at its upper end is placed an inferiorly threaded metal cap 7 which is also 80 flattened on its outer side as shown in Fig. 4, to prevent relative rotatory movement between the head and cap. The cap is larger 85 in diameter than the diameter of the upper reduced part 4 of the core so that its upper edge will abut against the shoulder 5 resulting from the different diameters of the core. The cap is cemented in place in the core, preferably by fire clay, or other heat-resist- 90 ing cement, and then the lower part of the core is closed by a plug 8, which is also cemented in place, preferably by fire clay. In order to more securely hold this plug in place, it may be provided with an annular 95 groove 9, and a coinciding annular groove 10 may be made around the interior of the core for receiving fire clay or other cementing material when the parts are assembled.

The shank of the paddle above the head 100 is preferably built up of separate sleeves or collars 11 of refractory material, like that of the head 1. These collars have their central openings of the same diameter, as the small part 4 of the core through the 105 head. The collars are usually cemented together and to the metal support 12 by fire clay or other suitable heat resisting material.

The support 12 for this paddle is a metal 110

tube, the lower end of which is threaded and screwed into the cap 7 that is held in the head. The upper end of the supporting tube may be threaded for receiving a nut 13 which may be utilized for supporting the tube on the holder or carrier 14 of the machine, in which this implement is to be used.

For the purpose of keeping the temperature of the supporting tube 12 below the point at which it would easily bend, a pipe 15 of smaller exterior diameter than the interior diameter of the supporting tube 12 extends through that tube, its lower end being centered with the nut 7 by means of a washer 17. The sides of the lower end of the pipe 15 are cut away, as at 18, thus opening it into the tube. The upper end of this pipe 15 may be held centrally with the tube 12 by screws 16, and it is designed to be connected with any suitable source of cooling air or other fluid under pressure, so that the cooling fluid will flow down through the pipe 15 to the head of the paddle, and return around the pipe 15, in such manner as to cool the pipe and the supporting tube 12 sufficiently to prevent them from being overheated.

With this construction the metal parts are protected from heat, and all expansion and contraction due to the heating of the paddle when it is operating on the hot molten glass and its cooling when removed therefrom can take place without subjecting any of the parts to undue strains such as would cause them to break or deteriorate.

The operating head may be of any form desired, for its intended functions as a stirrer, or paddle, or plunger, or for its mode of operation. The protecting collars 11 on the shank herein shown as being cylindrical may be of any cross section, or form, or length desired.

The metallic reinforcement, or support, is herein shown as being built up of standard commercial forms of piping, which are inexpensive, and easily obtainable almost anywhere. The reinforcement may, however, be made of cast metal, in one or more pieces, with passages drilled or cored therein for the circulation of the cooling fluid. Moreover, the reinforcing member may be of any desired cross section. When cylindrical members are employed some portions should be flattened as shown at 6, or otherwise made irregular in form to prevent the head and its reinforcing member from turning relative to each other.

The refractory material of the head which is herein shown as being built up of separate sections, may for some purposes be made in fewer pieces, or in a single piece, for purposes in which the expansion and contraction, to which it is liable, would not be sufficient to disrupt or seriously break

the head. Whenever such cracks occur they are liable to extend throughout the entire structure. It is for the purpose of avoiding these cracks, or at least to confine them locally, that the structure is preferably built up of separate sections, united by fire clay or other suitable heat resisting cement, which is more elastic or yielding than the more refractory material of which the exposed portions of the head are made. These joints permit of local expansion and contraction, and any cracking which may occur will usually be limited to the joints, or at least is not liable to extend across the joints from one section of the head to another.

In assembling these parts, the reinforcing member, if made of separate pieces as shown, is first put together, the nut 7 being screwed tightly upon the pipe 12. Then the reinforcing member is pushed through the head 2, from its lower end to the position shown in Fig. 1 and enough of the collars 11 are added to make up the desired length of shank, the cement being applied between the joints. Cement is then inserted into the core 3 around the collar 7, thus in effect "grouting" it in place, after which the plug 8 is inserted and some more of the cement, or grouting if put into the joint, filling up the annular grooves 9 and 10, thus effectively holding the plug in position when the cement is set. The supply pipe 15 may then be inserted to place and secured by screws 16.

When put into use, this implement may be held by any suitable form of chuck or holder 14. Connection may be made between the pipe 15 and any convenient supply of air or other cooling fluid under pressure, by means of an ordinary union coupling, as shown in Fig. 1. The connection from the union to the air tank or other source of supply may be made by a jointed or flexible pipe, in accordance with the common practice in glass working machines.

The invention claimed is:

1. An implement for working molten glass, including a head of refractory material having a shouldered opening through it and having a flat surface at one side of the opening, a tubular reinforcement extending into one end of the opening, a tube fastened within the reinforcement for conveying cooling fluid, an enlarged cap threaded to the reinforcement and flattened on one side to engage the flattened surface of the head and bearing against the shoulder of the opening, and a refractory plug closing the other end of the opening.

2. An implement for working molten glass having a tubular reinforcement, a refractory head with an opening through it mounted on the reinforcement and secured against rotation on the same, a tube for conveying cool-

ing fluid fastened within the reinforcement, and a refractory plug closing one end of the opening.

3. An implement for working molten glass having a tubular reinforcement, a refractory head with an opening through it mounted on the reinforcement and secured against rotation on the same, a refractory protecting shank mounted on the reinforcement above the head, a tube for conveying cooling fluid fastened within the reinforcement, and a refractory plug closing one end of the opening.

4. An implement for working molten glass having a tubular reinforcement, a refractory head with an annularly grooved opening through it mounted on the reinforcement, means for circulating cooling means through the reinforcement, and a refractory plug closing one end of the opening and having an annular groove to match that in the opening.

Signed at Hartford, Connecticut, this 26th day of March, 1917.

KARL E. PEILER.
